UNITED STATES PATENT OFFICE.

IVAN JAMES FROST, OF LYNN, MASSACHUSETTS, ASSIGNOR OF ONE-HALF TO MERTON WILDER, OF MANCHESTER, NEW HAMPSHIRE.

GARBAGE RECEIVER.

Application filed April 20, 1920. Serial No. 375,229.

To all whom it may concern:

Be it known that I, IVAN J. FROST, a citizen of the United States, and a resident of Lynn, county of Essex, and State of Massachusetts, have invented a new and Improved Garbage Receiver, of which the following is a full, clear, and exact description.

This invention relates to garbage receivers, and has reference more particularly to a 10 garbage receiver especially adapted to contain garbage cans.

An object of this invention is to provide a garbage receiver which may be placed in the ground so that its upper surface will be 15 level therewith.

Another object of this invention is to provide a garbage receiver for containing a garbage can in which the garbage receiver is provided with a removable bottom which 20 is perforated to allow the escape of any water collecting in the receiver, and is also adapted to prevent rats from entering the receiver.

A further object of this invention is to 25 provide a garbage receiver in which the cover may be moved by the foot to one side for the introduction of the garbage, and said cover will return to its normal position under spring action.

30 Reference is to be had to the accompanying drawing forming a part of this specification, in which it is understood that the drawing illustrates only one form of the invention, and in which—

35 Figure 1 is a plan view of the garbage receiver.

Figure 2 is a section through the receiver and garbage can on the line 2—2 of Figure 1.

40 Figure 3 is a sectional view through the receiver on the line 3—3 of Figure 2.

Figure 4 is a sectional view through the receiver on the line 4—4 of Figure 1.

45 Referring to the accompanying drawing by numerals, 10 indicates the wall of the receiver which is preferably cylindrical in shape, and which is provided on its lower end with an inwardly extending annular flange 11 adapted to support, inside said receiver, a removable bottom disc 12 provided with perforations 13, said perforations serving to allow the escape of any water collected in the receiver. The bottom 12 is made removable so that same may be removed for 50 cleaning the receiver, but said bottom will

prevent rats from entering therein. A plurality of chordally extending rods 14 are secured to the cylindrical wall 10 of the receiver by means of nuts 15 and said rods serve to support a garbage can 16 so that the bottom of said can will be spaced apart a short distance from the removable bottom 12, thus allowing air space so as to provide a free circulation of air and keep the inside dry. A cover 17 for the receiver is hinged by means of a pin 18 to the wall 10 of said receiver, and said cover is provided with an annular depending flange 19 adapted to fit closely around the wall 10 so as to prevent the escape of obnoxious odors from the garbage receiver. When the garbage can 16 is removed or inserted in the receiver, a handle 20 is provided on said cover so that the same may be moved about its pivot 18 to an open or closed position. The cover 17 is provided 70 with a co-axially positioned circular hole 21 through which garbage may be introduced into the garbage can 16, and said hole is covered by means of a circular closure or disc 22 pivoted by means of a pin 23 to the 80 cover 17, so that the cover 22 may be moved parallel to the cover 17 about said pin 23 to an open position by means of a lug 24 on said cover 22 which may be engaged by the foot. In order to normally maintain the 85 cover 22 in a closed position, a spring 25 is secured at one end to the underside of the cover 17, and at the other end to the underside of the cover 22, and a lug 26 is formed on the upper side of the cover 17 so as to 90 limit the further movement of the cover 22 under the action of the spring 25 when said cover 22 is in a closed position. It is preferable to provide means for removing the cover 22 for repairing or replacing and for 95 this purpose a radially extended lug 27 is provided on the pin 23 which will register with a slot 28 formed in the cover 17 so that said pin may be withdrawn from said cover 17. If so desired the receiver may be sunk 100 in the ground so that the cover 17 will be level with the surface of the ground.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claim.

Having thus described my invention, I claim as new and desire to secure by Letters Patent:

5 A garbage receiver open at the top, a cover hinged to the receiver and provided with a hand opening, a closure for the hand opening pivoted to the cover, the pivot pin having a lug to retain the closure in posi-

tion, and the cover having a slot to register with the lug in one position of the closure 10 to admit of its removal, a retractile spring connecting the closure with the cover and passing through the opening of the latter, and means for limiting the movement of the closure.

IVAN JAMES FROST.
